(57) **CLAIM**

The ornamental design for a rounded knee and shin pad, as shown and described.

DESCRIPTION

FIG. 1 is a front isometric view of a rounded knee and shin pad showing my new design.

FIG. 2 is a front elevation view thereof.

FIG. 3 is a top plan view, the bottom plan view being a mirror image thereof.

FIG. 4 is a rear elevation view thereof; and,

FIG. 5 is side elevation view thereof.

The broken lines define boundaries of the claimed design and form no part of the claimed design.
